UNITED STATES PATENT OFFICE.

JOHN SAKAC, OF CLEVELAND, OHIO.

SAFETY-ENVELOP.

1,246,166.

Specification of Letters Patent. Patented Nov. 13, 1917.

Application filed March 12, 1917. Serial No. 154,186.

To all whom it may concern:

Be it known that I, JOHN SAKAC, a subject of the King of Hungary, residing at Cleveland, in the county of Cuyahoga and State of Ohio, have invented certain new and useful Improvements in Safety-Envelops, of which the following is a specification.

This invention relates to certain new and useful improvements in safety envelops.

10 The primary object of the invention is the provision of an envelop structure adapted for securely inclosing a missive, the securing means being so arranged that any attempt to open the envelop may be readily detected.

20 A further object of the device is the provision of an envelop adapted to prevent surreptitious extraction of the contents thereof when the envelop is sealed in its closed position, interengaging sealing members being arranged for providing a secure closure and locking means for the device.

25 With these general objects in view and others that will appear as the nature of the invention is better understood, the same consists in the novel construction, combination and arrangement of parts hereinafter fully described, illustrated in the accompanying drawing and pointed out in the appended 30 claims.

In the drawing forming a part of this application and in which like numerals refer to corresponding parts throughout the several views,

35 Figure 1 is a developed view of the blank employed in forming the envelop.

Fig. 2 is a rear elevation of the envelop with the securing flap open.

40 Fig. 3 is a sectional view taken upon line III-III of Fig. 2.

Fig. 4 is a similar transverse sectional view of the device in its closed position, and,

45 Fig. 5 is an enlarged perspective view of the pocket forming arrangement of the lower flap.

Referring more in detail to the drawing, a blank 10 of the form illustrated in Fig. 1 of the drawing is provided formed of paper fabric or other desirable material, the same 50 having a rectangular body portion 11 and opposite similar end flaps 12 while side flaps 13 and 14, hereinafter designated as upper and lower flaps respectively are provided for coöperation therewith.

55 The so-called lower flap 14 is of substantially triangular shape being connected at

its base to the body 11 as at the line 15 upon which the flap 14 is adapted to be folded. An apron 16 projects outwardly from the apex of the flap 14 being foldable upon the line 17 for overlying a substantially triangular, or keystone shaped opening 18 in the flap 14 and to which flap the apron is secured by suitable adhesive matter 19 arranged adjacent the outer edges of the apron, it being understood that the apron 16 is secured in the manner noted overlying the inner face of the lower flap 14 and with said flap folded upon the line 15 adjacent the body 11. The end flaps 12 are folded inwardly overlying the flap 14 and secured thereby by the adhesive 20 upon the inner lower edges of the said end flaps. In this position, the envelop is in its completed form as illustrated in Fig. 2, the same being in a position to receive articles therein, the closure flap 13 being open.

The end flaps are provided with terminal extensions 21 which overlie the opening 18 and are adhesively secured to the inner face of the apron 16 positioned inwardly thereof, the end edges 22 of the extensions 21 being in substantially abutting engagement when so arranged and thereby providing a segmental entrance slot 23 for an arcuate tongue 24 provided at the extremity of the sealing flap 13, it being noted that the apron 16 forms a receiving pocket for the said tongue.

With the envelop formed as described and as best illustrated in Fig. 2 of the drawing, a desired article is placed within the envelop and the flap 13 folded downwardly upon the line at 25 for engaging the adhesive 26 at the free edges of the flap 13 with the outer sides of the end flaps 12 while the tongue 22 which is also provided with the adhesive, is thrust through the slot 23 and adhesively secured to the apron 16. An envelop is arranged which is cheap and easy to manufacture and which affords security in inclosing missives and articles, the structure being extremely difficult to open or unseal without such act being readily detected.

What I claim as new is:—

1. An envelop comprising a blank having a substantially triangular flap provided with a keystone shaped opening adjacent the apex thereof, a pocket forming apron attached to the apex with the flap adapted for overlying the said opening inwardly of the flap when in an envelop forming arrangement, opposite end flaps arranged overlying

the said triangular flap with extensions in end abutment with each other overlying a portion of said opening and secured to the apron forming an entrance slot and a closure member adapted for reception in the said slot.

2. An envelop comprising a blank having a substantially triangular flap provided with a keystone shaped opening adjacent the apex 10 thereof, a pocket forming apron attached to the apex with the flap adapted for overlying the said opening inwardly of the flap when in an envelop forming arrangement, opposite end flaps arranged overlying the said

triangular flap with extensions in end abutment with each other overlying a portion of said opening and secured to the apron forming a segmental entrance slot, a closure flap arranged opposite the said triangular flap formed with a terminal arcuate tongue 20 adapted for reception within the slot when the device is closed and adhesive material upon the said closure flap and tongue adapted for engagement with the said end flap extensions and apron when closed. 25

In testimony whereof I affix my signature.

JOHN SAKAC.

Copies of this patent may be obtained for five cents each, by addressing the "Commissioner of Patents, Washington, D. C."
